US00D911844S

(12) **United States Design Patent** (10) **Patent No.:** **US D911,844 S**
(45) **Date of Patent:** **** Mar. 2, 2021**

(54) **BOTTLE FOR A CLEANING DEVICE**

(71) Applicant: **Unger Marketing International, LLC**,
Bridgeport, CT (US)

(72) Inventors: **James M. Buckley**, New Hartford, CT
(US); **Joseph K. Patterson**, Monroe,
CT (US)

(73) Assignee: **UNGER MARKETING
INTERNATIONAL, LLC**, Bridgeport,
CT (US)

(**) Term: **15 Years**

(21) Appl. No.: **29/677,309**

(22) Filed: **Jan. 18, 2019**

(51) LOC (13) Cl. **09-01**

(52) U.S. Cl.

USPC **D9/521**; D9/530; D9/543

(57) **CLAIM**

The ornamental design for a bottle for a cleaning device, as shown and described.

DESCRIPTION

FIG. 1 is a perspective view of a bottle, showing our new design in a first embodiment;

FIG. 2 is a front view of the embodiment shown in FIG. 1;
FIG. 3 is a rear view of the embodiment shown in FIG. 1;
FIG. 4 is a side view of the embodiment shown in FIG. 1;
FIG. 5 is another side view of the embodiment shown in FIG. 1;

FIG. 6 is a top view of the embodiment shown in FIG. 1;
FIG. 7 is a bottom view of the embodiment shown in FIG. 1;

FIG. 8 is a perspective view of a bottle, showing our new design in a second embodiment;

FIG. 9 is a front view of the embodiment shown in FIG. 8;
FIG. 10 is a rear view of the embodiment shown in FIG. 8;
FIG. 11 is a side view of the embodiment shown in FIG. 8;
FIG. 12 is another side view of the embodiment shown in FIG. 8;

FIG. 13 is a top view of the embodiment shown in FIG. 8;
and,

FIG. 14 is a bottom view of the embodiment shown in FIG. 8.

The broken lines in the figures are for environmental purposes only and form no part of the claimed design.

1 Claim, 12 Drawing Sheets
